UNITED STATES PATENT OFFICE.

EMIL BEROLZHEIMER, OF NEW YORK, N. Y., ASSIGNOR TO EAGLE PENCIL COMPANY, OF SAME PLACE.

DESIGN FOR A DISPLAY-BOX FOR PENCILS, PENHOLDERS, &c.

SPECIFICATION forming part of Design No. 34,529, dated May 21, 1901.

Application filed April 22, 1901. Serial No. 57,028. Term of patent 14 years.

To all whom it may concern:

Be it known that I, EMIL BEROLZHEIMER, of the city, county, and State of New York, have invented a new and original Design for 5 Display-Boxes for Pencils, Penholders, &c., of which the following is a specification, reference being had to the accompanying drawing, which represents in perspective a box embodying my invention.

10 The box is divided into compartments A by partitions, the external face of each of which represents a column or, more correctly speaking, a pilaster, of which *a* is the shaft, *b* is the capital, and *c* the pedestal. On three edges—
15 the bottom and two side edges—the walls of the

box are straight. The fourth or top side of the box has, however, the form of a pediment *d*, which surmounts the columns or pilasters and bounds the compartments A at that end.

What I claim, and desire to secure by Letters Patent, is—

The design for a box substantially as herein shown and described.

In testimony whereof I have hereunto set my hand this 19th day of April, 1901.

EMIL BEROLZHEIMER.
